[57] CLAIM

The ornamental design for a combination watch holder and water-tight container, as shown and described.

DESCRIPTION

FIG. 1 is an exploded view of a first embodiment of a combination watch holder and water-tight container of my invention with the cover removed;

FIG. 2 is a top perspective view of the first embodiment of the combination watch holder and water-tight container;

FIG. 3 is a side view of the first embodiment of the combination watch holder and water-tight container;
FIG. 4 is a top perspective view of a second embodiment of the combination watch holder and water-tight container of my invention;

FIG. 5 is an exploded view of the second embodiment of the combination watch holder and water-tight container with the cover removed;

FIG. 6 is a side view of the second embodiment of the combination watch holder and water-tight container;

FIG. 7 is a top perspective view of a third embodiment of the combination watch holder and water-tight container of my invention;

FIG. 8 is a top view of the third embodiment of a combination watch holder and water-tight container;

FIG. 9 is an exploded view of the fourth embodiment of the combination watch holder and water tight container of my invention; and,

FIG. 10 is a side view of the cover of the fourth embodiment of my invention.

The broken-line showings of a cord in FIGS. 1-6 are for environmental purposes only and forms no part of the claimed design.
